COMBINATION TOOL

Filed Dec. 31, 1927

By his attorney G. A. Logan
Inventor: G. A. Logan
G. F. Beeler

UNITED STATES PATENT OFFICE

GEORGE A. LOGAN, OF NEW YORK, N. Y.

COMBINATION TOOL

Application filed December 31, 1927. Serial No. 243,819.

This invention relates to tools or instruments of the general type described and claimed in my Letters Patent of the United States No. 1,667,462 of April 24th, 1928.

5 Among the objects of the invention is to enlarge the field of usefulness of this tool so as to provide for a more flexible interchange of instrument blades or attachments with respect to a common handle and to facilitate 10 such interchange in an easy practical manner.

More definitely stated, the general object and scope of this invention is comprehended in a construction involving a handle, a tool 15 or blade socket in the nature of a hub journaled permanently in said handle so as to be swung into open or closed position, and a series of blades, tools, or other instrumentalities adapted to be inserted selectively and 20 interchangeably into said socket piece or hub.

With the foregoing and other objects in view the invention consists in the arrangement and combination of parts hereinafter 25 described and claimed, and while the invention is not restricted to the exact details of construction disclosed or suggested herein, still for the purpose of illustrating a practical embodiment thereof reference is had to 30 the accompanying drawings in which like reference characters designate the same parts in the several views, and in which—

Figure 1 is a plan view of a blank from 35 which a preferred form of the handle mechanism may be formed from sheet metal.

Fig. 2 is a side view of the handle completed.

Fig. 3 is a plan view of the blank that may 40 be used for forming the socket piece or hub.

Fig. 4 is a side view of the same completed. Fig. 5 is an edge of the socket piece.

Fig. 6 is a side view of a tool blade in the 45 form of a sharp pointed file adapted for use in said socket piece and handle.

Fig. 7 shows the assemblage of the blade of Fig. 6 in the handle and socket piece.

Fig. 8 is an enlarged sectional detail on the 50 line 8—8 of Fig. 7.

Fig. 9 is a side view of a different type of

blade or blade holder having the same shank attachment for connection with the hub.

Fig. 10 is a preferred form of cutting blade for use in the holder of Fig. 9.

Fig. 11 is an enlarged sectional detail on 55 the line 11—11 of Fig. 9.

Fig. 12 is a blank showing one way of forming the holder of Fig. 9.

Fig. 13 is a side view of a different type of 60 blade.

Fig. 14 is a still further form of interchangeable blade or tool.

Referring now more specifically to the drawings, I show a handle 15 formed as shown in Fig. 1 from a sheet metal blank 65 having two cheek plates 15a and 15b foldable into parallel planes along a back or rib 16 and provided with registering holes 17 and 18 at or near its opposite ends, the holes 17 for a hanger or link 19, and the other 70 holes for a pivot pin 20. These cheek plates are spaced from each other as shown in Fig. 8. The pivot end of the handle is formed on arcs of circles at 21 approximately concentric with the pivot holes 18, and the adjacent 75 end of the rib 16 constitutes a shoulder at 22.

The hub or socket member of Figs. 3, 4, 5, and 7 is shown as a whole at 23 and comprises two substantially similar cheek plates or disks 24 having registering holes 18a and 80 a central connecting web 25 which in the finished structure, as shown in Figs. 4 and 7, constitutes a shoulder adapted to abut against the shoulder 22 in the open position of the instrument. It will be understood that 85

the socket member is so formed as to provide an open space or socket 26 bounded on one side by the shoulder web 25 and on the opposite side by a closed web 27. Also it will be 90

noted that the socket member otherwise is approximately circular and with the pivot holes 18a central thereof and adapted to register with the pivot holes 18 of the handle and through all of which holes the pivot pin 95

20 passes fastening the handle and socket member permanently together. The socket member is of relatively thin structure and operates in the space between the side plates or cheek pieces 15a and 15b of the handle. These two parts may be held from free rela- 100

tive rotation by friction or any other suitable means, as, for instance, the positive locking means as shown in the previous application above mentioned. As thus far described it will appear that the socket 26 of the socket member or hub 23 constitutes an opening into which any desired blade, tool, instrument, or the like, may be inserted and manipulated through the handle.

10 Fig. 6 shows a blade in the nature of a file 28 having a nail cleaning point 29 and a slotted shank portion 30 at its opposite end for insertion directly into the socket 26, the slot 31 receiving at this time the pivot pin 20. 15 The parts are so made that they are retained normally in connection by friction, but they may be separated by drawing the two parts directly away from each other. Fig. 13 shows a different type of blade in the nature 20 of a surgeon's lance 32 provided, however, with a similar socket 30 and slot 31 for the purposes stated above. The preferred form, however, of detachable or interchangeable instrumentality is shown in Fig. 9 which 25 constitutes a holder 33 of sheet metal formed from the blank as shown in Fig. 12 and comprising two side portions 34 and 35, at least one of which is provided with an integral shank portion 30a having a slot 31. At the 30 end of the holder 33 remote from the shank there is provided a locking pin 36, and while the main portions of the sides 34 and 35 may be approximately parallel to each other and slightly spaced, they are preferably swaged 35 inward toward each other at their mid portions as shown at 37 for the purpose of gripping tightly upon the sides of a blade 38 adapted for co-operation with such holder.

The blade 38 has a sharp cutting edge 39 40 and is made preferably of substantially rectangular form but provided at its ends with a pair of notches 40 and 41, each end design being a duplicate of the other. The blade body is made preferably of uniform thickness 45 and approximating the normal space between the side pieces 34 and 35 of the holder but greater in thickness than the space at the swaged portion 37. With either end of the blade inserted into the holder as shown in 50 dotted lines in Fig. 9, the notch 40 at such end will receive the pin as an anchor means or fulcrum and then the back edge of the blade will be forced directly into the channel of the holder where it will be gripped snugly 55 as shown in Figs. 9 and 11 and where the device may be used as a sharp cutting knife or scraper when the holder shank 40a is inserted into the socket piece 23. The holder and blade therein may be swung around into 60 the handle in a manner similar to the action of a knife blade in an ordinary knife handle for carrying purposes and swung outward into open position for cutting purposes. The hole or notch 40 at the opposite end of 65 the blade from the one already described is

normally idle but the notch 41 adjacent thereto is employed for the application of a pry tool or instrument such as a small coin indicated at C in Fig. 9 which may be inserted between the end of the blade and the adjacent end of the handle for the purpose of starting the blade outward from the holder for the purpose of turning the blade end to end or for the interchange of one blade for another. Obviously when one end or point of the blade 38 becomes dulled the other end may be turned for use by removing the blade as just described and turning it end to end and inserting it as before described. Fig. 14 gives a suggestion of a still further modification of instrumentalities, the same comprising a holder 33a in the nature of a safety razor guard and adapted to receive and hold any suitable blade for shaving or other purposes, but provided with a shank 30b having a notch or slot 31 made to conform to the socket 26 in the socket piece in which it is adapted to be used interchangeably the same as all the other devices set forth herein. It will be understood that many other forms of blades or tools may be used in this manner provided they are provided with shanks adapted to fit into the socket piece interchangeably. As a commercial proposition, these handles, socket pieces, and blade instrumentalities are made in sets so that a single handle and socket piece may be used for any desired number of blades interchangeably.

I claim:

1. In a combination tool, a handle, a hub in the handle for engaging a tool means, said hub consisting of a single sheet of material comprising a plurality of cheek plates interconnected by a web, another oppositely positioned split web, and pivot means passing through the cheek plates and mounting the hub on the handle, one of said webs coacting with the handle as a stop.

2. In a combination tool, a handle having a circular end, pivot means thereon at said end, a hub on the pivot means, said hub consisting of a single piece of sheet material comprising a plurality of cheek plates interconnected by a web, and means including a tool holder having a slotted end received in the hub, and with the slot receiving the pivot means, said tool holder having pin means at the free end thereof, and a blade positioned in the said holder, said blade having a recess at one end to engage the pin means, and a recess at its opposite end adjacent to the center line of the handle through the center of said circular end, the last mentioned recess being outside of the tool holder whereby the blade may be pried out thereof with the circular end of the handle acting as a pivot.

3. In a combination tool, a handle, pivot means thereon, a hub on the pivot means, said hub comprising a plurality of cheek plates, interconnected by a web, and means includ-

ing a tool holder having a slotted end received in the hub, and with the slot receiving the pivot means, said tool holder having pin means at the free end thereof, and a blade 5 positioned in the said holder, said blade having a recess at one end to engage the pin means, and a recess at its opposite end normally exposed from the holder to permit of engagement of the blade for removal thereof, 10 the body of the holder being to one side of the axis of the handle, the end of the blade adjacent to the handle being spaced therefrom for easy access of the exposed recess and to permit the application of a pry thereto with 15 the adjacent end of the handle acting as a pivot.

In testimony whereof I affix my signature.
GEORGE A. LOGAN.
